UNITED STATES PATENT OFFICE.

WILLIAM B. KING, OF BOSTON, MASSACHUSETTS, ASSIGNOR TO UNITED SHOE MACHINERY COMPANY, OF PATERSON, NEW JERSEY, A CORPORATION OF NEW JERSEY.

WELT-CONTROLLING MECHANISM.

1,071,435.

Specification of Letters Patent. Patented Aug. 26, 1913.

Application filed March 7, 1912. Serial No. 682,243.

To all whom it may concern:

Be it known that I, WILLIAM B. KING, a citizen of the United States, residing at Boston, in the county of Suffolk and State 5 of Massachusetts, have invented certain new and useful Improvements in Welt-Controlling Mechanism; and I do hereby declare the following to be a full, clear, and exact description of the invention, such as will enable others skilled in the art to which it 10 appertains to make and use the same.

The invention relates to welt controlling mechanism for inseam sewing or other machines for attaching welts to shoes.

15 In removing a shoe from an inseam sewing machine after the sewing of the seam has been completed the welt is drawn forward through the welt guide and is severed near the end of the seam either by the operator or by welt severing devices incorporated in 20 the machine. In the former case, the surplus welt drawn forward by the operator in removing the shoe should be drawn back, leaving the proper length of welt projecting 25 through the welt guide, while in the latter case the forward movement of the welt as the shoe is withdrawn should be arrested after the proper length of welt has been drawn forward through the welt guide.

30 It is the object of the present invention to provide novel and improved mechanism for controlling the welt after the completion of the sewing operation, so that the proper length of welt is left projecting beyond the welt guide preparatory to the sewing of another shoe.

To this end the invention comprises the features of construction and combination of parts hereinafter described and referred to 40 in the claims.

The invention is illustrated as embodied in a mechanism constructed and arranged to draw back any surplus welt which may have been drawn forward by the operator 45 in removing the shoe to a position where he may conveniently sever the welt, although various features of the invention are applicable to and may be embodied in controlling mechanisms for limiting the withdrawal of the welt to the amount requisite 50 for bringing the welt into proper position to be severed by welt severing devices.

The various features of the invention will be readily understood from an inspection 55 of the accompanying drawings, and the fol-

lowing description of the construction illustrated therein.

In the drawings, Figure 1 is a side elevation of an inseam sewing machine provided with a welt controlling mechanism embodying the features of the present invention in their preferred forms; Fig. 2 is a plan view of the welt controlling mechanism; Fig. 3 is a detail side elevation, partly in section, of a part of the mechanism; Fig. 4 is a vertical sectional view through the axis of the welt guiding roll; and Fig. 5 is a detail sectional view illustrating certain parts of the mechanism.

The machine illustrated in the drawings is provided with a needle 1, a feed point 2, channel guide 3, looper 4, thread finger 5, back rest 6, and the usual coöperating devices for forming and setting the stitch and feeding the shoe. The machine is also provided with a welt guide 7 for guiding and holding the welt adjacent to the sewing point. These parts may be of any usual or well-known construction, and are operated in the usual manner. In addition to these devices, the machine is also provided with a welt controlling mechanism embodying the various features of the present invention, and constructed to draw back a length of welt less by a predetermined amount than the length drawn forward by the operator in removing the shoe, so that the proper length of welt will remain projecting beyond the welt guide ready for the succeeding sewing operation. As shown, 90 this mechanism comprises a guide roll or pulley 8 about which the welt passes on its way to the welt guide. The welt is led from the welt supply over a guide roll 9 so arranged that the welt wraps about a considerable portion of the periphery of the guide roll 8. The movements given to the welt after the completion of the sewing operation are determined by a controller which in the construction shown comprises a drum 10 mounted to turn upon a stud 11 and provided with a hub sleeve 10' on which the guide roll 8 is mounted to turn freely. During the sewing the roll 8 turns idly, so that the welt may feed freely to the shoe. After the completion of the sewing operation the pulley, or welt, or both are connected to the controller drum 10 by a clamp 12 carried on the controller drum and arranged to engage the welt and clamp it against the pe-

periphery of the roll 8 so that the roll, welt and controller will move together.

The clamp is carried on one arm of a bell crank lever 13 pivoted on the drum 10 and having its arm extending radially to the axis of the drum. The lever is normally forced in a direction to hold the clamp out of engagement with the welt by a spring 14. The lever is moved in a direction to engage the clamp with the welt through a rod 15 mounted within the stud 11. The front end of the rod engages the inner end of the bell crank lever, and the rear end of the rod is engaged by one end of a lever 16. The lever 16 is actuated at the completion of the sewing operation to force the clamp against the welt through a link 17 which passes through one arm of a bell crank lever 18, the other arm of which carries a lever 19. The rear end of the link 17 is provided with nuts 20, and a spring 21 is interposed between the nuts and the arm 18, so that the clamp will be forced yieldingly against the welt by movement of the bell crank lever 18. The lever 19 is provided with two segmental bearing surfaces 22 and 23, one or the other of which engages the periphery of a collar 24 secured to the cam shaft 25 of the machine.

During the sewing, the bearing surface 22 rides against the periphery of the collar 24, and the parts are held in the position indicated in the drawings, with the clamp free of the welt so that the welt is free to move forward as the feed of the shoe progresses. When the sewing operation has been completed, and the cam shaft of the machine is turned back to bring the thread handling devices into position for removal of the shoe, and to relieve the tension in the usual manner, a notch 26 in the collar 24 engages the projection between the segmental surfaces 22 and 23 and swings the lever 19 toward the right, at the same time depressing it so that the bell crank lever 18 is rocked to force the clamp 12 against the welt. This connects the controller drum 10 with the welt and guide roll 8 so that the controller drum rotates with the guide roll 8 when the welt is drawn forward, and the movement of the welt is controlled by controlling the movement of the controller.

In the construction shown the controller drum is held yieldingly in normal position by a spiral spring 27, one end of which is secured to the drum and the other end of which is secured to the stud 11. The normal position of the controller is determined by an adjustable stop screw 28 arranged to be engaged by the pivot pin 29 of the clamp carrying lever 13. When the welt is drawn forward by the operator in removing the shoe at the completion of the sewing operation, the spring 27 is wound up, and when the welt is severed from the shoe the spring

acts to return the drum 10 and roll 8 and thus draw the welt back through the welt guide. The return movement of the controller and pulley is arrested, however, before they reach their normal or initial position, so that a proper length of welt is left projecting beyond the welt guide. The devices for thus arresting the controller comprise a stop lever 30 the lower end of which is arranged to coöperate with a stop dog 31 pivoted on the drum 10, and the other end of which is provided with a hole surrounding the end of the rod 15. A spring 32 is interposed between the lever 30 and a collar 33 on the rod, so that the movement of the rod may continue after the stop lever has reached the limit of its movement. The stop dog 31 is held yieldingly in position by a spring 34 which will yield to allow the stop dog to ride idly by the stop lever when the controller moves forward with the welt, but will retain the dog in position to engage the stop lever during the return movement of the controller drum. The stop lever is projected into the path of the stop dog by the movement of the rod 15 which engages the clamp 12 with the welt at the completion of the sewing operation. The length of welt left projecting beyond the welt guide may be varied by the adjustment of the stop 28 which determines the initial position of the controller and the normal position of the stop dog 31 with relation to the stop lever 30.

At the beginning of the sewing operation the clamp 12 is actuated to free the welt, and the stop 30 is withdrawn from active position to allow the controller and clamp to be returned to initial position and to allow the welt to move forward independently of the controller as the sewing progresses. This is accomplished automatically by the forward rotation of the cam shaft which returns the lever 19 to the position indicated in Fig. 1, thus relieving the pressure on the rod 15 so that the spring 14 may rock the bell crank lever 13 to disengage the clamp, and to shift the stop lever from active position.

The return movement of the controller drum 10 and guide roll 8 by the spring 27 may be controlled by a retarding device so that accurate positioning of the welt is insured. In the construction shown the retarding device comprises a piston 35 connected with the hub of the controller drum 10 and arranged to reciprocate in a cylinder 36. The rod of the piston is provided with a rack 37 engaged by a pinion 38 which is connected through gears 39 and 40 with the hub 10' of the controller drum. The lower end of the cylinder is connected through a pipe 41 and check valve 42 with a tank 43 containing oil or other suitable liquid. A small pipe 44 forms a bypass around the check valve 43 which is controlled by an adjust-

able valve 45. As the controller is rotated in a forward direction by the drawing forward of the welt, the piston 35 rises and the liquid flows freely from the tank 43 through the check valve 42. When the controller is rotated in the reverse direction by the spring, the check valve closes and the flow of the liquid from the cylinder to the tank is controlled by the bypass, which may be adjusted to secure the desired retarding effect.

10 The tension of the spring 27 which returns the controller may be varied as desired by loosening the nut 46 on the rear of the stud 11 to allow the position of the stud to be varied. After the tension of the spring has been adjusted the parts may again be clamped in position by tightening the nut 46. The front end of the stud is provided with a polygonal head to receive a wrench by which the stud may be turned to secure the proper adjustment.

15 While it is preferred to employ the specific construction and arrangement of parts shown and described, it will be understood that this construction and arrangement is not essential except so far as it is specified in the claims, and that it may be varied and modified without departing from the broader scope of the invention. It will also be understood that the invention may be embodied in other forms of welt controlling devices.

20 Having explained the nature and object of the invention, and specifically described one form of mechanism in which it may be embodied, what I claim is:—

1. A welt controlling mechanism, having, in combination, a guide roll for the welt, a clamp, a clamp carrier mounted to turn with the roll about the axis of the roll, means for rendering the clamp inactive during the sewing, and means for engaging the clamp with the welt at the completion of the sewing, substantially as described.

2. A welt controlling mechanism, having, in combination, a guide roll for the welt, an independently movable clamp carrier concentric with the roll, a clamp, means for rendering the clamp inactive during the sewing, means for engaging the clamp with the roll at the completion of the sewing, and means for returning the clamp carrier to initial position, substantially as described.

3. A welt controlling mechanism, having, in combination, a guide roll, a clamp carrier concentric with the roll, a clamp arranged to clamp the welt on the roll, means for rendering the clamp inactive during the sewing, and means for engaging the clamp with the welt at the completion of the sewing, substantially as described.

4. A sewing machine, having, in combination, stitch forming mechanism, a controller drum, means for retaining the drum in normal position during the sewing, and means

rendered active previous to the withdrawal of the shoe for causing the drum to be rotated by the welt, substantially as described.

5. A sewing machine, having, in combination, stitch forming mechanism, a controller drum, means for retaining the drum in normal position during the sewing, and means rendered active in bringing the machine into position for the removal of the shoe for causing the drum to be rotated by the welt, substantially as described.

6. A welt controlling mechanism, having, in combination, a welt retractor constructed to move forward with the welt as the shoe is withdrawn, a spring for returning the retractor to draw back the welt, and a retarding device for regulating the return movement of the retractor, substantially as described.

7. A welt controlling mechanism, having, in combination, a guide roll for the welt, a clamp carrier concentric with the roll, a clamp, a spring for holding the carrier in normal position, means for actuating the clamp, a stop for arresting the carrier before it completes its return movement, and means for rendering the stop inactive, substantially as described.

8. A welt controlling mechanism, having, in combination, a guide roll for the welt, a clamp carrier concentric with the roll, a clamp, a stud on which the clamp carrier is mounted, a spiral spring connecting the stud and clamp carrier, and means for adjustably securing the stud in position, substantially as described.

9. A sewing machine, having, in combination, stitch forming mechanism, a guide roll for the welt, a sleeve on which the roll is mounted, and means for connecting the welt, roll and sleeve at the completion of the sewing, substantially as described.

10. A sewing machine, having, in combination, stitch forming mechanism, a guide roll for the welt, a sleeve on which the roll is mounted, a welt clamp carried by the sleeve, a stop for limiting the rotation of the sleeve, and means for engaging the clamp with the welt at the completion of the sewing, substantially as described.

11. A sewing machine, having, in combination, stitch forming mechanism, a guide roll for the welt, a clamp, a clamp carrier mounted to turn with the roll, and means for actuating the clamp to grip the welt in bringing the sewing mechanism into position for removal of the shoe, substantially as described.

12. A sewing machine, having, in combination, stitch forming mechanism, a guide roll for the welt, a clamp, a clamp carrier mounted to turn with the roll, and means for actuating the clamp to grip the welt in bringing the sewing mechanism into position for removal of the shoe and for actu-

ating the clamp to free the welt during the sewing, substantially as described.

13. A welt controlling mechanism, having, in combination, a guide roll for the 5 welt, a clamp carrier concentric with the roll, a clamp on the carrier, an arm connected with the clamp, an actuator engaging the arm substantially in the axis of the carrier, and means for operating the actuator to render the clamp inactive during the sewing and to engage the clamp with the 10 welt at the completion of the sewing, substantially as described.

14. A welt controlling mechanism, having, in combination, a guide roll, a clamp 5

carrier concentric with the roll, a clamp on the carrier, an arm connected with the clamp, an actuator engaging the arm substantially in the axis of the carrier, a spring for holding the clamp carrier in normal position during the sewing, and means for operating the actuator to render the clamp inactive during the sewing and to engage the clamp with the welt at the completion of the 25 sewing, substantially as described.
